UNITED STATES PATENT OFFICE.

WILHELM SCHUMACHER, OF OSNABRÜCK, GERMANY, ASSIGNOR TO GENERAL BRIQUETTING CO., OF NEW YORK, N. Y., A CORPORATION OF MAINE.

BRIQUETTING-PRESS.

1,322,960.

Specification of Letters Patent. Patented Nov. 25, 1919.

Application filed December 2, 1912, Serial No. 734,442. Renewed December 16, 1918. Serial No. 137,443.

To all whom it may concern:

Be it known that I, WILHELM SCHUMACHER, a citizen of the German Empire, and a resident of Osnabrück, in the Kingdom of Prussia, Empire of Germany, have invented certain new and useful Improvements in Briquetting-Presses, of which the following is a specification.

The invention relates to presses for making briquets, and more particularly to the style of presses known as lever presses, and has for its object to provide means for obtaining without any increase in power briquets of greater thickness and of more uniform firmness throughout than heretofore obtained in briquets compressed in lever presses.

It is old in lever presses to have the active or positively operated die (whether it be the upper die or the lower die) mounted resiliently, so that as soon as a certain pressure is attained or exceeded this die will become stationary or even recede. The object of this arrangement is on the one hand to avoid breakage of the press as a result of excessive pressure, on the other hand to provide means for regulating the pressure exerted upon the material to be compressed so that a uniform amount of pressure can be maintained, any excess of pressure being taken care of by the resiliency of the die. As in lever presses the pressure exerted upon the material to be compressed is dependent upon the amount of material put into the mold. This amount is so regulated that the pressure will become somewhat greater than the pressure at which the resiliently mounted active die will become stationary. The stopping or receding of the resiliently mounted die thus serves to indicate that a certain degree of pressure has been attained or exceeded.

The exertion of the active pressure against the material from but one side results in the disadvantage that the part of the material adjoining the active die is subjected to a greater pressure than the material on the opposite side of the mold. Experiments made with a briquet having a cross-section of 250x125 millimeters have developed the fact that up to 40% of the power used for operating the press is consumed by friction between the material to be compressed and the side walls of the mold, as a result of which the upper part of the briquet is sub-

jected to a smaller amount of pressure than the rest of the briquet, and consequently does not become as dense or as firm as the other part of the briquet.

I have discovered that this drawback may be overcome by combining with a resiliently mounted die, a mold arranged to slide in the direction of the pressure exerted upon the material to be compressed. The result of this arrangement is that the lever press will have an action like that of a hydraulic press—that is to say the entire material to be compressed into briquets will be subjected to a uniform pressure, not from one side only but from both sides so that briquets of the same firmness may be made twice as thick as formerly without requiring any increase of the power employed to operate the press.

A specific example of my invention is shown in the accompanying drawings it being understood that I do not restrict myself to this particular embodiment. Figure 1 shows a vertical section of the machine in which the upper die is resiliently mounted; Fig. 2 is a similar view showing both dies resiliently mounted; Fig. 3 represents a mold and lower die in section; and Fig. 4 represents a non-resilient upper die.

A designates the stationary frame of the press, provided with upright rods A', one of which forms an axle for the mold carrier or mold table B, rotated intermittently by suitable mechanism (not shown) and provided with (say, twelve) vertical through openings B'. In each of these is adapted to slide vertically arranged a mold C, open at the top and at the bottom, and normally resting on an apertured supporting plate B² secured to the mold table B. In the construction shown, the lower die D is the active or power die, being operated by a plunger D' suitably guided in the frame A. There is a die D for each mold C, adapted to move up and down therein, which dies D travel with the table, coming, one by one, into registry with the plunger D'. By this arrangement the molds C are slidable in the pockets or openings B' in the direction of movement of the dies D and the dies D are slidable relatively to the associated molds. Any suitable connection between the molds and dies D to permit the relative movement thereof may be used such, for instance, as shown in Fig. 3 of the drawings. The mold and die are of

- sufficient weight to be restored to normal position by gravity after displacement during the operation of the machine. After the completion of a briquet the die D is utilized 5 to eject the finished briquet, the movements of the dies D, except when under pressure, being controlled by a circular cam path substantially in accordance with the principles of the Brück-Kretschel press.
- 10 The plunger D' is connected pivotally at D² with a link E the lower end of which is pivoted at E' to the operating lever F fulcrumed on the frame at F'. A connecting rod G is pivoted at G' to the operating 15 lever F and at G² to a crank H upon a countershaft J which is driven from the main shaft K by means of toothed gearing L.

In the press illustrated by Figs. 1 and 2 20 of the drawings the upper die M is a counterdie or backing, that is to say, it braces the material to be compressed, against the action of the power die D. The counterdie M is mounted resiliently, as by having it 25 movable in a stationary cylinder A². A pipe N connects this cylinder with a tank O the upper part of which contains a fluid under pressure, say nitrogen compressed to 135 atmospheres. The hydraulic cylinder 30 A², the pipe N and the lower part of the tank O are filled with oil or other suitable liquid. P designates a pressure gage and Q a valve controlling the connection of the tank O with the pipe N. Other means than 35 the one shown may be employed for mounting the counterdie M yieldingly.

The means for filling the molds C and for 40 ejecting the finished briquets are not shown, and may be of any well-known or approved construction.

The operation is as follows:

In the filling position, the molds C rest 45 on the plate B², as shown at the left in the drawing, and the power die D is in its lower position. The upper die or counterdie M is always clear of the mold table B, that is to say, the lower face of the die M is always above the upper face of the mold table. The intermittent rotation of the table B brings 50 the molds C, one by one, to the pressure position shown at the right in the drawing, except that at the beginning of the compressing operation the filled mold still rests on the supporting plate B² and the power die D is in its lower position. As the operating lever F is swung upward, the plunger D' and the power die D are forced upward, compressing the filling or material E in the mold C, against the counterdie M. Instead 55 of wasting a large amount of power in overcoming friction between the material and the side walls of the mold (as would be the case if the mold were not movable vertically) practically the entire pressure is utilized to 60 compress the filling, since the mold rises to 65

the position shown, so as to fit around the counterdie M. The amount of friction between the material and the sides of the mold C is thus minimized, and the efficiency of the press increased correspondingly.

When the pressure exerted by the power die D exceeds a certain limit, the counterdie M will yield upwardly in the cylinder A², the resulting increase of pressure being indicated by the gage P. This resilient 75 mounting of the counterdie will prevent the occurrence of excessive strains which might deform or break parts of the machine.

The briquet having been formed as described, the power die D recedes to its lower 80 position, the mold C at the same time dropping back upon the plate B². Then occurs another partial rotation of the table B and the ejection of the briquet from the mold, according to the usual procedure.

Instead of being stationary, as shown in Fig. 1, the fulcrum F' of the operating lever F (as shown in Fig. 2) might be carried by the upper end of a vertically movable plunger S, similar to the counterdie M, the lower 90 end of said plunger working in a cylinder T corresponding to the cylinder A², and in connection with this cylinder I would provide a tank O', pipe N', pressure gage P' and cock Q' of the same character as shown 95 at O, N, P and Q respectively, with the filling of oil and nitrogen or other compressed fluid as explained above. The nitrogen tank should preferably be located about three feet above the level of the hydraulic cylinder 100 with which it is connected. It will be readily understood that by securing the fulcrum F' to a yielding or hydraulic plunger as just described, an elastic mounting is provided for the power die D. Thus if a certain pressure is exceeded, the hydraulic pressure which normally holds the fulcrum F' stationary, will be overcome, the die D becoming stationary or even receding slightly. Of course the counterdie M would also recede 110 as described above, but to a smaller extent than when only the counterdie is mounted resiliently. It will further be obvious that when the power die D is mounted resiliently as explained above, the counterdie M might 115 be stationary or rigid, instead of yieldingly mounted which can be accomplished by using a solid die M' such as shown in Fig. 4. When both dies are mounted yieldingly, each of them will act on the liquid in the 120 respective hydraulic cylinder, whenever the desirable pressure is exceeded, and on account of the better distribution of the resilient action, this resilient mounting of both dies may be preferred in some cases.

Various modifications may be made without departing from the nature of my invention as set forth in the appended claims.

I claim:

1. In a briquetting press, the combination 130

of oppositely disposed dies, means for causing one die to approach the other to compress material therebetween, the last named die remaining relatively fixed until the pressure exceeds a predetermined amount, means which permits the relatively fixed die to recede when the predetermined pressure is reached and simultaneously increases the pressure on the material being compressed, and a movable mold in which said dies operate, said mold being adapted to be moved in the direction of movement of the dies, by reason of its frictional engagement with the material under compression.

15 2. In a briquetting press, the combination of an upper die, a mold movable beneath

said upper die and into exact registry therewith, a movable sleeve in said mold, a lower die, means for actuating said lower die, and means for permitting said upper die to yield 20 when a predetermined pressure upon the material under compression is exceeded and for concurrently increasing the pressure exerted upon said material.

In testimony whereof, I have hereunto set 25 my hand in the presence of two subscribing witnesses.

WILHELM SCHUMACHER.
